UNITED STATES PATENT OFFICE.

JOHN SCOTT-TAGGART, OF LONDON, ENGLAND, ASSIGNOR TO COMMERCIAL CABLE COMPANY, OF NEW YORK, N. Y.

ELECTRON-DISCHARGE DEVICE.

Application filed November 30, 1920. Serial No. 427,410.

(GRANTED UNDER THE PROVISIONS OF THE ACT OF MARCH 3, 1921, 41 STAT. L., 1313.)

To all whom it may concern:

Be it known that I, JOHN SCOTT-TAGGART, a subject of the King of Great Britain, residing in London, England, have invented 5 certain new and useful Improvements in Electron-Discharge Devices (for which I have filed applications in England, dated 17 Sept., 1919, Serial No. 22,863, Patent No. 166,260, and dated 5th Nov., 1920, Serial 10 No. 31,376, Patent No. 179,568), of which the following is a specification.

This invention relates to electron discharge devices or thermionic valves especially for use in wireless signalling, and has 15 for its object to enable such devices to be applied as substitutes for negative resistances or for amplification or for other purposes in the art of wireless communication.

20 It is well known that in ordinary electron discharge devices or valves an increase in the positive potential of the anode with respect to the cathode causes an increase in the anode current, also known as a space 25 current. According to the present invention an opposite effect is obtained with a single valve or electron discharge device having two or more anodes, by a redistribution of the electrons passing from the cathode to 30 the anodes which does not depend upon the liberation of secondary electrons on one of the anodes, but upon the diversion to one of the anodes of electrons emitted by the cathode, that is, space current, which would 35 otherwise pass to the other anode or anodes and the consequent reduction of current from the cathode to the first anode.

This redistribution of electron current 40 may be consequent upon a variation of potential of a control electrode or grid or of one of the anodes which are so disposed and connected with respect to each other and the other elements of the valve as to effect the result described.

45 For a better understanding of the operative principle of the device which will be hereinafter identified as a negatron valve or negatron, reference is made to the accompanying drawings wherein Fig. 1 is a dia- 50 grammatic view of one form of the device; Fig. 2 a similar view embodying a modification; Figs. 3 and 4 are diagrams illustrating the application of the invention to amplifying purposes; Fig. 5 is a diagram illus-

trating its use to provide a circuit having 55 a falling voltage-current characteristic, that is, a circuit wherein an increase in voltage produces a decrease in current, and vice versa. Figs. 6 and 7 show modifications of Fig. 1.

60 In Fig. 1 the two anodes A, B, which for convenience of reference will be called the A anode and the B anode respectively, are in the form of flat plates arranged parallel with each other on opposite sides of 65 an electron-emitting cathode such as a filament F heated to incandescence and of a control electrode or grid G, all being contained in an evacuated vessel, e. g. an evacuated glass bulb. Batteries C, D, E are 70 connected with the various elements as shown. The battery E gives the grid G a suitable operating potential, preferably negative with respect to the cathode F. The batteries C and D are so connected with the 75 anodes and cathodes as to make the anodes positive with respect to the cathode and so cause a flow of electrons through the evacuated space from the cathode to the respective anodes. Batteries C, D and E are 80 of course chosen of proper voltages to cooperate with the characteristics of the vacuum tube, and are preferably adjustable in this respect, as is usual in apparatus of 85 this nature and as shown in the various figures. These electron currents will be referred to as the A anode current and the B anode current respectively. The grid G is connected to the anode A by a circuit including a battery E, preferably adjustable 90 as shown in Fig. 1, so as to impress any desired potential on the grid.

95 If we assume that the electrode G is given by means of variable source E a potential sufficiently negative to that of the cathode F to reduce the B anode current to a low value, there will be a steady A anode current whose magnitude is determined by the operating characteristics of the cathode, and the difference of potential applied between 100 cathode F and anode A, in other words by the normal impedance of this combination of cathode and anode. By normal impedance is meant the impedance existing between an anode at a normal operating potential and the cathode at a normal operating temperature, when said two factors alone serve 105 to determine the value of the impedance;

that is, if there be an interposed grid, when said grid has no bias such as would change the value of the electron flow. If now the existing positive potential of A with respect to the cathode F is increased, there will be a corresponding increase in the potential of G with respect to F, that is, G will become less negative to the cathode F. Consequently a larger B anode current begins to flow, and assuming that the cathode F be operated so as to provide a saturation condition, some of the electrons which normally would flow from F to A are diverted to B, and the normal A anode current is correspondingly reduced, instead of increasing as it would if the elements F and A alone were present, upon increase of the potential of A. The circuit ACF thus possesses a falling voltage-current characteristic which may be utilized to offset or neutralize wholly or partially the resistance of a circuit inserted in the ACF circuit, that is, the current in such circuit may be made larger for a given applied voltage than it would be without the aid of the ACF circuit.

The diminution of A anode current due to diversion of electrons to the B anode may more than counteract the normal increase of A anode current due to increase of A anode potential, in which case the device acts as stated above, or the diversion effect may be the less in value, in which case the device would act as an ordinary resistance, or the two effects could be made to balance each other so that the A anode current would not be affected by any variation of the potential of A within certain limits. The diversion effect of the control electrode G may be varied in a number of ways, by altering the operating conditions, for example the filament temperature, or suitably modifying the relative positions of the electrodes.

If it is desired to overcome the resistance in a conducting circuit it is only necessary to connect such a circuit in the A anode circuit. By connecting an external resistance circuit in series with the A anode circuit and making the resistance such that the rising voltage-current characteristic due thereto is nearly offset by the falling voltage-current characteristic of the ACF circuit, the device will act as a very efficient voltage amplifier. If the external resistance be connected in parallel with the A anode circuit, for instance to A and F, the device will act as a current magnifier.

It is to be noted that the device operates entirely on the principle of the diversion to a B anode or anodes of electrons, that is, space current, which would otherwise pass to the anode A. The same effect could not be produced by the use of two valves.

It may be desirable to use one battery in place of the two batteries C and D. It may

also be desirable to include an adjustable resistance between the battery supplying a positive potential to A and the anode A itself.

A suitable wireless receiving circuit may be arranged by placing the receiving oscillatory circuit in series with the A anode circuit of the negatron. In addition, a pair of telephones shunted by a variable condenser may be included in series with the circuit, as shown in Fig. 6.

Another useful circuit is obtained by taking the leads from the positive side of C and the anode A and connecting them across the control electrode and cathode of a simple three-electrode device wireless receiving circuit. This neutralizes losses in the control electrode circuit of the three-electrode device. This is illustrated in Fig. 7.

In the above description, by the A anode circuit is normally meant the external path taken by current corresponding to electrons going to the A anode. Similarly, by B anode circuit is meant the external path taken by current corresponding to electrons going to the B anode.

In the arrangement shown in Fig. 2 the negatron valve contains two anodes A and B respectively arranged on opposite sides of the cathode filament F. A control electrode G is suitably placed to control the electron current flowing from F to B. The A anode circuit includes an indicator I and a battery C and the B anode circuit includes a battery D.

The electron current from the filament F distributes itself over the divided paths available, and the temperature of the filament is adjusted so as to make the total electron emission from the filament approximately that corresponding to a saturation condition and which is equal to the sum of the electron currents in the two anode circuits. Under these conditions an increase of potential of the electrode G with respect to the cathode F (that is, making the electrode G less negative or more positive) will produce a decrease of current in the A anode circuit and an increase in the B anode circuit. The negatron valve therefore acts to produce a decrease of current to one of the anodes which is not due to absorption of electrons by the control electrode or grid G, but to the diversion of current to the other anode.

Such a valve may be applied to the production of various effects. Fig. 3 shows an arrangement of circuits in which the valve is used as an amplifier. A common battery C' for the two anode circuits is shown, although separate anode batteries can be used as in Fig. 2. The A anode circuit includes also an indicator I and a resistance R. The potential of the grid G may be given a suitable value by means of a battery E or equiv-

alent device. Terminals J, H are indicated for the connection of the input circuit which is preferably conductive.

If the input E. M. F. increases the potential of grid G with respect to the cathode F, the A anode current will decrease, and the change of current in the resistance R communicates an added positive potential to the grid G, reinforcing the original applied potential. The added positive potential above mentioned is produced as follows: When a current i is flowing through R there is a potential drop, iR , between the ends of said resistance, the end remote from the positive pole of battery C' being at the lower potential. If i decreases, the product iR also decreases, that is, the drop is less, or the potential of the remote end of R rises. Inasmuch as this end is connected (through battery E) to the grid G, the said grid G will also acquire an added positive potential. Large changes of current, as indicated by the measuring device I, can thus be obtained in the A anode circuit.

If the constants of the several circuits be suitably selected the device may be employed as a relay.

In the modified arrangement for using the negatron as an amplifier illustrated in Fig. 4, a resistance R' is included in the A anode circuit and a resistance R^2 in the B anode circuit. If a potential positive with respect to the cathode be applied to the control electrode G, the B anode current will increase, thus making the lower end (as shown in the diagram) of the resistance R^2 more negative because of the increased drop of potential due to the greater current through resistance R^2 . At the same time the A anode current will decrease, similarly, making the upper end of resistance R' more positive. There results from this a magnified potential difference between the output terminals Y, Z.

In the arrangement illustrated in Fig. 5 showing the utilization of the falling voltage-current characteristic of the device to counteract a resistance, the reduced current effect in the A anode circuit enables the effective resistance in a circuit to be reduced e. g. by inserting it between the terminals K, L in the A anode circuit. An oscillatory circuit O may be connected between these terminals as indicated for the purpose of producing continuous oscillations. Oscillations produced in this circuit arise by virtue of the falling voltage-current characteristic of the A anode circuit. Both in this case and in the amplifying arrangement illustrated in Fig. 3, the change of potential due to change of current in the resistance R may be amplified before being applied to the grid G.

It will be obvious that the indicating device I may be included in the B anode cir-

cuit in the several arrangements hereinbefore described, since a variation in the A anode current is always accompanied by an opposite variation in the B anode current. Also the B anode circuit may be used as the output circuit in arrangements using the negatron.

In all uses of the negatron such as herein described the diversion effect may be adjusted by altering the strength of the filament current, an increase of which diminishes the extent to which current is diverted from one anode to another.

While some methods of using the negatron have been suggested, many additional applications of the device will occur to those skilled in the art.

Having thus described the nature of the said invention and the best means I know of carrying the same into practical effect, I claim:

1. The combination with a thermionic device having a plurality of anodes, a cathode, and a control electrode cooperating with said cathode, and with one of said anodes, of a circuit containing inductance and capacity connected between the cathode and another of the anodes, means maintaining a difference of potential between said last named anode and the control electrode and means maintaining potential differences between both said anodes and the cathode.

2. A thermionic device having a cathode, a plurality of anodes, and a control electrode in the electron path between the cathode and one of said anodes, means for causing electrons to flow from the cathode to said anodes and means whereby some of the electrons normally passing from the cathode to one of the anodes are diverted to another anode when the potential of the former anode with respect to the cathode is increased.

3. The combination in a vacuum tube of a cathode, and two anodes, means for causing a flow of electrons from said cathode to both of said anodes, and means for varying the potential of one of said anodes with respect to the cathode, and means for causing the flow of electrons to said anode to be increasingly diverted to the other as the said potential of the first named anode is increased.

4. In a vacuum tube having a cathode and two anodes so placed that space currents may pass between said cathode and both said anodes in separate paths, having no portion in common, the method of controlling the current in one of said paths which comprises diverting electrons therefrom to the other path by and in proportion to potential difference increases set up at the extremities of said first named path.

5. In a vacuum tube having a cathode and a plurality of anodes the method of controlling a space current between the cathode

and one of said anodes which comprises setting up another space current between said cathode and another of said anodes, maintaining the operating conditions such that
5 the sum of said space currents remains substantially constant, and causing said second space current to vary in the inverse sense to the variation desired in the first current.

6. A vacuum tube having a cathode and
10 two anodes arranged to provide two inde-

pendent electron paths, one of said paths being of substantially lower normal impedance than the other, a control electrode interposed in the said lower-impedance path, and means for maintaining said anodes positive with respect to the cathode.

In testimony whereof I have signed my name to this specification.

JOHN SCOTT-TAGGART.
